CLAIM

The ornamental design for an electronic device with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with animated graphical user interface showing a first image of the claimed design;

FIG. 2 is a second image thereof;

FIG. 3 is a third image thereof;

FIG. 4 is a front view of another embodiment an electronic device with animated graphical user interface showing a first image of the claimed design;

FIG. 5 is a second image thereof;

FIG. 6 is a third image thereof;

FIG. 7 shows the design of FIG. 1 applied to another electronic device.

FIG. 8 shows the design of FIG. 2 applied to another electronic device;

FIG. 9 shows the design of FIG. 3 applied to another electronic device;

FIG. 10 shows the design of FIG. 4 applied to another electronic device;

FIG. 11 shows the design of FIG. 5 applied to another electronic device; and,

FIG. 12 shows the design of FIG. 6 applied to another electronic device.

The broken lines in the figures show an electronic device having a display screen, and form no part of the claimed design.

The appearance of the animated image sequentially transitions between the images shown in FIGS. 1-3 and FIGS. 4-6. The process or period in which one image transitions to another forms no part of the claimed design.
